BALL HOLDING ATTACHMENT FOR BELTS

Osbjorn Bratene, 1137 Chancer St. 32806, and David F. Marocco, 1428 E. Burton St. 92805, both of Anaheim, Calif.

Filed May 15, 1975, Ser. No. 577,935

Term of patent 14 years

Int. Cl. D2—07

U.S. Cl. D2—400

FIG. 1.

FIG. 2.

FIG. 3.

FIG. 4.

FIG. 5.

FIG. 6.

FIG. 7.

FIG. 8.

FIG. 1 is a top left, front perspective view of a ball holding attachment for belts showing our new design; FIG. 2 is a right side elevational view thereof;

FIG. 3 is a rear elevational view thereof;

FIG. 4 is a bottom plan view thereof;

FIG. 5 is a top left, front perspective view of another embodiment of our new design of FIG. 1 wherein there are three ball holders instead of one;

FIG. 6 is a right side elevational view of FIG. 5;

FIG. 7 is a rear elevational view of FIG. 5; and

FIG. 8 is a bottom plan view of FIG. 5.

We claim:

The ornamental design for a ball holding attachment for belts, as shown.
